UNITED STATES PATENT OFFICE.

EDWARD F. SHELLABERGER, OF DE KALB, ILLINOIS.

WIRE-FABRIC MACHINE.

SPECIFICATION forming part of Letters Patent No. 633,870, dated September 19, 1899.

Application filed July 26, 1899. Serial No. 725,193. (No model.)

To all whom it may concern:

Be it known that I, EDWARD F. SHELLABERGER, of De Kalb, in the county of De Kalb and State of Illinois, have invented certain new and useful Improvements in Wire-Weaving Machines, of which the following is a specification.

This invention relates to certain improvements in wire-weaving machines, and is particularly adapted to the weaving of wire fences composed of a series of longitudinal strands with which are interwoven transverse stays or pickets.

The object of the invention is to provide a machine of this kind having a capacity for producing the fabric rapidly, the machine being so organized that the transverse stays or pickets do not require any shaping or forming previous to being fed into the machine.

The machine is adapted to the making of a fabric composed of longitudinal cables, each formed of two wires twisted together with single-wire pickets or stays; but in a modified construction I show provisions for making a fence fabric composed of longitudinal strands, some of which are cables and some single wires, with single-wire pickets or stays connecting the series of strands transversely. A machine designed to weave a fence

composed of longitudinal cables and transverse stays or pickets, wherein the wire from which the pickets are formed is fed at intervals across and between the strands of the cables and twists therewith, is shown in Letters Patent No. 622,406, issued to me as assignee of Charles E. Warner April 4, 1899. In the machine of that patent provisions are shown for deflecting the picket-wire between the strand wires or cables in order to provide the necessary slack for permitting the formation of the loop or wrap of the strands around the cables. My invention is an improvement upon the machine of that patent in several respects, which will be made apparent in the following description, and the features of novelty will be pointed out in the claims.

Figure 1 is a plan view of my improved machine, except the reels and reel-holders for supplying the wire. Figs. 2 and 3 are opposite side elevations of that part of the machine shown in Fig. 1. Fig. 4 is a partial sectional elevation taken on the line 4-4 of Fig.

1, particularly showing the picket-wire feed and three of the twisters. Fig. 5 is a detailed view, in cross-sectional elevation, taken at 55 right angles to the view shown in Fig. 4. Figs. 6, 7, and 8 are detailed views of the twister-heads. Figs. 9 and 10 are detailed views of the fabric particularly intended to show the twisted loops thereof. Fig. 11 is a detailed 60 view showing the knife for severing the picket or stay and its operating mechanism. Fig. 12 is a side elevation showing in detail the cams and the mechanisms operated thereby in the formation of the loop. Fig. 13 is a 65 side elevation of the rack-bar for rotating the twister-heads and its driving mechanism; and Figs. 14 to 18, inclusive, are views showing a modified construction to adapt the machine to the weaving of a fabric where- 70 in the pickets are interwoven with single-wire strands or a combination of single-wire strands and cables.

The machine shown in the accompanying drawings and from which said drawings were 75 made is adapted to weave fabrics of varying widths up to sixty-three inches and contains twelve twister-heads, each adapted to carry two wires, which are cabled or twisted together, with provisions for regularly moving 80 such wires, cabling them, feeding in the picket or stay wire, interweaving it at the points of intersection, cutting off the picket-wire, wrapping the severed ends around the marginal cables, straightening the body of the stay or 85 picket between the loops, and drawing out the finished fabric.

The operative parts are mounted upon the framework 20, which affords a support for the boxes of the several shafts, of which 21 is 90 the driving-shaft geared to the counter-shaft 22, carrying a series of gear-wheels and cams for driving various operative mechanisms and the reel-shaft.

The drawings show the machine with the 95 parts in the position they occupy during the deflection of the picket-wires to provide the necessary slack for the formation of the loops and just prior to the operation of the twisters to form said loops.

Mounted upon a vertical extension 23 of the frame 20 are two shafts 24 25, carrying a series of sheaves 26 27, which lead the wires 28 29 into the rear end of the twisters 30.

The bodies of these twisters have longitudinal channels for the wires, these channels opening at their forward ends into a chamber 31, extending transversely through the end of the twister-head and open at its ends for the passage of the picket or stay wire. The extremity of the twister-head is slotted, as shown at 32, such slot leading into the chamber 31, thus forming upper and lower jaws 33 34, having parallel faces. In Fig. 6 one of the twisters is shown in longitudinal sectional elevation, its journals being marked 35 and its driving-gear 36. The twister-heads being disposed in the same horizontal plane and with their gears 36 in alinement, they are simultaneously driven by means of a rack 37, mounted upon a sliding bar 38. Endwise-reciprocating motion is imparted to this rack-bar by the means shown in Figs. 1, 3, and 13, the rack-bar having a downwardly-extending arm 39, to which is connected a pitman 40, pivotally connected to a sliding cross-head 41 and carrying a perforated plate 42, which serves as a rack, centering-pins 43, and curved segmental guides 44, all projecting transversely from the side of the cross-head. A gear-wheel 45 is mounted with its teeth in line with the perforations of the rack-plate 42 on a shaft 46, provided with a sliding block 30 or box 47, moving in a guideway 48, the shaft having a universal-joint or knuckle connection at its opposite end with a short driving-shaft 49, driven intermittently by the beveled pinion 50 and mutilated gear 51 on shaft 22. Obviously the rotation of the cam-shaft 22 driving the shafts 49 and 46 intermittently will result in rotating the gear 45 in the direction of the arrow. The gear is provided with a pin 45^a , which is shown in Fig. 13 in contact with the inner surface of the curved guide 44. The gear has two of its teeth cut away, and between them is formed a depression or seat 45^b for the centering-pin 43. When rotation is imparted to the gear 45, it will be caused by reason of the pins 43 and 45^a to draw the cross-head 41 inward until the teeth of the gear engage the perforations on the under side of the rack-plate 42, thus imparting a stroke to the cross-head, which terminates as the gear reaches the corresponding position at the opposite end of the rack, when it comes to rest. In the return movement the gear will travel upon the upper side of the rack-plate and cause the movement of the cross-head and therefore of the rack-bar 38 in the opposite direction.

Assuming now that the wires 28 and 29 are properly threaded through the twister-head, the rotation of the twisters would result in twisting or cabling said wires together. In order to connect the cables transversely, the pickets or stays are fed in from the side of the machine, as shown in Fig. 4. The picket-wire (marked 52) is drawn from a coil or spool between the feed-rolls 53, driven by the gears 54, the pinion 55, idler 56, and driver 57, arranged in the usual manner, so as to give a fast or

slow speed. The wire 52 is fed through the enlarged chambers 31 of the twisters, being guided thereto by the funnel-shaped guides 70 58, one of which is mounted upon the framework adjacent to each twister-head. The wire 52 in feeding in passes between the strand-wires 28 29 back of the crotch or point of crossing of the latter and is projected entirely across the fabric and beyond the margin thereof sufficiently to provide for the amount of wire taken up in forming the twisted loops. On a twenty-four-inch fabric composed of seven cables the loops take up from six to seven inches, depending upon the size of the wire. The wire 52 after being fed across between the strands of the cables, with its leading end projecting beyond the last cable, is held in that position by the feed, the movement of which is arrested. The intermittent feed is provided for by the employment of the mutilated gear 59 on the cam-shaft 22, which drives intermittently the pinion 60 on shaft 61, which carries the gear 57. The next operation consists in deflecting the body of the wire 52 between successive cables. In my machine this deflection is in a horizontal plane or the plane of the fabric and in the direction of its travel. The deflection is accomplished by means of a series of vibrating levers 62, pivoted between their ends upon pivots 63 and carrying at their extremities adjustable blocks 64, provided with rollers 65. These rollers contact with cams 66, the cams being mounted upon a shaft 67, driven from the shaft 22 by means of the mutilated gear 68 enmeshing pinion 69 on shaft 70, having a beveled gear 71 driving a similar gear 72 on the shaft 67. One of these levers 62 is arranged to project into each of the spaces between the longitudinal strands of the fabric, and in the inactive positions the upper end of the lever is back of the path of the picket or stay wire 52 as it feeds forward across the fabric. During such position the lean side of the cam 66 is presented opposite the roller 65. The cams 66 are so disposed upon their shaft as to come into action successively, the cam on the feeding-in side of the machine being first brought into action. As the roller travels up the incline of the cam its lever moves forward, striking the wire 52 between the first pair of cables and deflecting the body of said wire, which is yet unsevered and held in the guide of the feeding mechanism. The body of the wire resting between the cables is drawn into the crotch of the second pair and the deflected portion is held in that position until successive deflections are produced between each pair of cables by the successive action of the series of levers 62. The cams are so arranged as to all become inactive at the same time, being successively shorter from the feed side of the machine. In order to prevent their sudden backward movement and yet allow them to yield while the loops are being formed, each of the levers 62 is backed up by a spring 73. The

springs 73 are mounted upon hubs 73^a, secured upon the rock-shaft 73^b, having a crank-arm 73^c, to which is connected an operating-lever 73^d, which is reciprocated by the cam 73^e, thus holding the spring 73 under tension against the rear sides of the levers 62. As a further provision for insuring the proper position of the wire 52 within the chambers 31 of the twisters I employ a series of pivoted 10 guides comprising a block 74, carried by an arm 75, fixed on a rock-shaft 76, having an operating-crank 77, which is vibrated by lever 78, provided with an antifriction-roller 79, which is engaged by cam 80 on the shaft 22. The cam 80 is so positioned as to operate immediately after the fabric is drawn forward and before the stay-wire is fed in. The blocks are positioned so as to coöperate with the funnels 58, the latter being slotted on 20 their front sides, as shown at 58^a, the blocks dropping down in front of said slots.

The cut-off mechanism for the stay-wire is shown in detail in Fig. 11 and comprises the fixed shearing-block 81, with which a knife 82 coöperates. The knife-bar is pivoted at 83, and its lower end has a retracting-spring 84 attached thereto which normally holds the upper end of the knife-bar against the stop 85, and pivoted lever 86 has one end thereof 30 positioned to engage the lower end of the knife-bar, while its opposite end is in the path of a pin or stud 87, mounted on one of the cam-disks 66. The position of the pin 87 determines the time of the cut, which immediately precedes the twisting.

The pull-out mechanism may be of any desired construction; but I have shown the mechanism for driving it arranged with particular reference to the action of the twisters, which is an important consideration, as will be hereinafter explained. As shown, the fabric is drawn out over the series of drums 88 89 90 and thence carried back to the spooling-drum 91. The series of drums 45 88 89 90 are geared together, and the drum 89 carries a beveled gear 92, driven by a pinion 93 on the shaft 94, having a gear 95, which is intermittently driven by the mutilated gear 96 on the shaft 22. With reference to 50 Fig. 1 it will be seen that the tooth parts of the mutilated gears 51 and 56 are so disposed that the gear 51, which drives the twisters, comes into action first, so as to form the loop in the stay-wire before the pull-out gear comes 55 into action. When the pull-out starts, the twister is still in action, and the stay-wire will continue to be twisted or wrapped around the cables until the crown of the loop passes beyond or out of the jaws of the twister. In 60 heavy wire it will not be necessary to give more than a half-twist to the base portions of the loop; but in light wire it would be preferable to give a complete wrap or twist of the stay-wire around the strand or cable wires. 65 This might be done by making the jaws longer or by providing the gear 51 with more teeth, so as to commence the twisting action

farther in advance of the pull-out. The spool or reel 91, on which the fabric is wound into rolls, is driven by the belt 97, running from pulley 98 on shaft 22 over a pulley 99 on the reel-shaft. This belt is provided with a suitable tightener 100 and is intended to slip as the diameter of the roll increases, so as to drive the reel slower.

In order to straighten out any kinks, deflections, or crooked portions remaining in the stay or picket after the twisting operation ceases, I employ a straightening mechanism, which is clearly shown in Fig. 12. A series 80 of blocks 101 are mounted on a bar 102, extended transversely across the machine, in front of the twisters, and carried by arms 103, secured with a rock-shaft 104, having a crank 105, which is moved by a lever 106, having a 85 roller 107, arranged in the path of a cam 108 on the shaft 22. The blocks 101 are shown in Fig. 12 below the plane of the fabric in order to permit the latter to feed forward, and as the cam comes into action it rocks the shaft 90 104, throwing the blocks 101 into the path of the wires, as shown in dotted lines in Fig. 5.

In order to arrest the cam 66 in proper position for each actuation, I preferably provide a flat-sided stop-block 109 on the shaft 67 and 95 arrange to coöperate therewith a lever 110, carrying shoe 111, the lever being reciprocated by a cam 112, against which it is normally held in contact by the spring 113. The forward end of the lever 110 passes through the 100 hanger 114. The cam 112 is so set with reference to the flat-sided block 109 that as the shaft 67 completes its revolution the flat side of the block and the flat side of the shoe are brought into face contact, thus holding the 105 cams 66 in proper position, or rather preventing them from being carried beyond proper position by momentum or arrested before reaching proper position by inertia.

Describing now the complete operation of 110 the machine and assuming that the strand-wires have been threaded through the twister-heads and twisted beyond the ends of the twisters, with the crotch of the last twist resting within the jaws and the stay-wire passed 115 between the strand-wires in each twister-head and projected beyond the last cable, thereupon the cam 66 next the feeding-in side of the machine comes into action and vibrates its lever 62, deflecting the said wire between 120 the first pair of cables, followed by the action of the next cam and its lever, and successively deflecting portions of the said wire across the fabric. The knife then acts and severs the stay from the wire, and then all of 125 the cams 66 simultaneously release, leaving the series of arms 62 held in position by their springs 73 and maintaining the stay-wire suitably deflected across the fabric. The twisters then begin their rotation, forming the loops, 130 and at the conclusion of the loop formation the pull-out mechanism comes into action, drawing out the fabric while the twisters are still rotating. So long as the loop of the fabric is

within the jaws of the twister the wrapping of the stay-wires around the strand-wires continues. As soon as the loop passes beyond the grasp of the jaws the strand-wires simply twist upon each other, and the pulling out of the fabric and the twisting of the cable-strands proceed simultaneously. As the fabric is drawn out the formation of the loops is intended to take up the slack and to straighten the deflected portions of the stay-wires; but in order to give a better finish to the fabric the stay-wire-straightening mechanism previously described comes into action at each forward movement of the fabric, the blocks 101 engaging any forward deflections or bends in the stay-wire and the latter being straightened by the time the fabric comes to rest.

In Figs. 14 to 18, inclusive, I have shown additional mechanism whereby the machine is adapted to the weaving of a fabric composed of single-wire longitudinal strands and transverse stays. The twister is modified by the omission of one of the longitudinal perforations, if desired, or it may have two perforations, one of them only carrying a strand-wire. Each twister is provided with a longitudinally-extending channel 115, leading to the slot 32 in front of the chamber 31. Within this channel is pivoted a finger 116, with its point adapted to be brought into contact with the surface of the jaw 34 in front of the stay-wire 52, so as to prevent the latter from being drawn out through the slot by the action of the deflecting-levers. The finger 116 is formed with a rearwardly-projecting bent arm, the extremity of which has oppositely-inclined portions 117 118, resting within a correspondingly-formed slot 119 in a collar or sleeve 120, mounted to rotate with the twister. The side of the latter may be flattened or provided with a channel corresponding to the slot 119 in the collar. An arm 121 has a pin engaging a groove 122 in the collar, and said arm projects rearwardly and is connected to a sliding bar 123, which is actuated by a lever 124, extending into bearing proximity to a cam 125, which may be on the shaft 22. In Fig. 16 the finger is shown depressed in front of the stay-wire, thus restraining it from forward movement during the action of the deflecting-levers. The finger is moved to and held in this position by means of the collar, which is pressed forward by the action of the cam, which is so timed as to hold the finger down until the fabric is ready to pull out. The forward movement of the fabric will rock the finger upon its pivot, and the inclines on the extremity of the arm will force the collar backward and place the extremity of its controlling-lever in position to be again engaged by the cam. By means of this addition to the mechanism a fabric composed of single-strand wires and transverse stays may be produced.

65 The machine of my present invention is particularly adapted to the economical production of a fabric for wire fencing—such as

shown in my Patent No. 623,841, dated April 25, 1899, which illustrates the same fabric shown in the drawings, Figs. 9 and 10. This fabric is distinguished by the fact that the stay-wires have loops extending at an angle to the body of the stay-wire and parallel to the cable, with the crown of the loop embraced between the strands of the cable and the end portions of the loop being turned, respectively, over and under and embracing both strands of the cable, extending therefrom in opposite directions to the adjacent cable. The construction would be essentially the same if a single-wire strand were used, except that the loop in that case would not be embraced between two strand-wires. In the Warner patent, to which I have previously alluded, the fabric has loops interlocked with the strand-wires; but said loops lie in the plane of the stay-wire instead of being angularly disposed thereto. My machine is distinguished from the said Warner machine not only in the particular construction of its twisters, but in the fact that it omits numerous parts necessary to the operation of said patented machine, such as the independent jaws for clenching or setting the loops. In my machine the stay-wires are deflected in the plane of the fabric, and this is made possible by reason of the peculiar construction of the twisters, which enables the stay-wire to be deflected forwardly without withdrawing it from the loop-forming mechanism. In my construction also the last twist of the cable remains within the grasp of the jaws and the looping is performed not by the twisting of the cable-wires, as in the previous construction, but by the jaws of the twister.

I claim—

1. A twister for wire-weaving machines adapted to carry a strand-wire and having a transverse slot in its extremity affording jaws, separated to permit a stay-wire to be projected between them and adapted when the twister is rotated to engage the stay-wire on opposite sides of the strand-wire to form a loop in the stay and interlock said loop with the strand, substantially as described.

2. A twister for wire-weaving machines adapted to carry a pair of strand-wires and having its extremity slotted to provide a pair of jaws separated to permit a stay-wire to be projected between them and adapted when rotated to engage the stay-wire to form a loop in the stay and interlock said loop with the strands, substantially as described.

3. In a wire-weaving machine, the combination, with means for feeding a stay-wire across a series of strand-wires, of a series of twisters having transversely-slotted ends affording jaws which engage the body of the stay-wire on opposite sides of the strands and by their rotation form loops therein and twist them about the strand-wires, substantially as described.

4. In a wire-weaving machine, the combination, with means for feeding a stay-wire

- across a series of strand-wires, of a series of 5
twisters carrying the strand-wires and having
transversely-slotted ends affording jaws
which engage the body of the stay-wire on op-
posite sides of the strands and by their rota-
tion form loops therein and twist them about
the strand-wires, and means for deflecting
the body of the stay-wire between adjacent
strands, substantially as described.
- 10 5. In a wire-weaving machine, the combi-
nation, with a series of twisters for carrying
strand-wires, means for feeding a stay-wire
transversely across the series of strand-wires
and means for deflecting the body of the stay-
15 wire between adjacent strand-wires, said
means comprising a series of pivoted levers
and cams for actuating said levers success-
ively, substantially as described.
- 20 6. In a wire-weaving machine, the combi-
nation, with a series of twisters for carrying
strand-wires, of means for feeding a stay-wire
transversely across the series of strand-wires
and means for deflecting the body of the stay-
25 wire between adjacent strand-wires, said
means comprising a series of pivoted levers
and cams for actuating said levers success-
ively, and springs for yieldingly holding said
levers in contact with the stay-wire after the
30 cams become inactive, substantially as de-
scribed.
- 35 7. In a wire-weaving machine, the combi-
nation, with a series of twisters carrying
strand-wires, means for feeding and severing
the stay-wire, levers for deflecting the stay-
40 wire between the strands, cams for actuating
said levers and a stop mechanism for arrest-
ing said cams in proper relation to the levers,
substantially as described.
- 45 8. In a wire-weaving machine, the combi-
nation, with a series of twisters for carrying
strand-wires, of means for feeding a stay-wire
across the strands and interlocking it there-
with, rack-gearing for rotating the twisters,
50 a pull-out mechanism and gearing for driv-
ing the same, the twister-driving gear and
the pull-out-driving gear being arranged in
such relation to each other that the pull-out
begins before the twisting action ceases, sub-
stantially as described.
- 55 9. In a wire-weaving machine, the combi-
nation with a series of twisters for carrying
strand-wires, said twisters having driving
gears, of a sliding rack intermeshing said
gears and means for sliding said rack com-
60 prising a rack-plate connected thereto and a
pinion for driving the rack, the pinion having
a movable bearing and guides whereby it
is caused to travel upon opposite sides of the

plate during the reciprocations of the latter, substantially as described. 60

10. In a wire-weaving machine, the combi-
nation with a series of twisters, each adapted
to carry strand-wire and having jaws for
looping a stay-wire and interlocking it with
the strand-wires, means for feeding the stay-
65 wire between the jaws, means for deflecting
the body of the stay-wire between the strands
and means for holding the stay-wire between
the deflected portions and within the grasp
of the jaws, substantially as described. 70

11. In a wire-weaving machine, the combi-
nation with a series of twisters for carrying
strand-wires, of means for feeding a stay-wire
across the body of said strand-wires, means
for deflecting the stay-wire in the plane of the
75 fabric and means for straightening the de-
flected portions, comprising blocks pivotally
mounted and adapted to be projected and
held in the path of the fabric as the latter is
drawn out, substantially as described. 80

12. In a wire-weaving machine, the combi-
nation with a series of twisters for carrying
strand-wires, each twister having its end
transversely slotted to provide jaws, means
for projecting a stay-wire across the strand-
85 wire between said jaws and slotted guides
mounted adjacent to the jaws of each twister
for guiding the end of the stay-wire, substan-
tially as described.

13. In a wire-weaving machine, the combi-
nation with a series of twisters for carrying
strand-wires, each twister having its end
transversely slotted to provide jaws, means
for projecting a stay-wire across the strand-
95 wire between said jaws and funnel-shaped
guides mounted adjacent to said jaws and
slotted on their forward sides to permit the
fabric to be drawn out, substantially as de-
scribed. 100

14. In a wire-weaving machine, the combi-
nation with a series of twisters for carrying
strand-wires, each twister having its end
transversely slotted to provide jaws, means
for projecting a stay-wire across the strand-
105 wire between said jaws, and funnel-shaped
guides mounted adjacent to said jaws and
slotted on their forward sides to permit the
fabric to be drawn out and movable blocks
adapted to close the slots of the guides dur-
ing the feeding in of the stay-wire, substan-
110 tially as described.
